United States Patent Office.

EDGAR A. JONES, OF STURGIS, MICHIGAN.

Letters Patent No. 90,947, dated June 8, 1869.

IMPROVED VELOCIPED.

The Schedule referred to in these Letters Patent and making part of the same.

To whom it may concern:

Be it known that I, EDGAR A. JONES, of Sturgis, in the county of St. Joseph, and State of Michigan, have invented a new and useful Improvement in Velocipedes; and I do declare that the following is a true and accurate description thereof, reference being had to the accompanying drawings, and to the letters of reference marked thereon, and being a part of this specification, in which—

Figure 1 is a perspective view of my invention, and Figure 2 is a detached section of the tiller, forked reach connections, and axle-jaws.

Like letters indicate like parts in each figure.

The nature of this invention relates to an improved construction of three-wheeled velocipedes; and consists in the peculiar arrangement of a tiller for directing the course of the steering-wheel, which is at the rear of the vehicle, and in providing the cranked axle with weighted stirrups, so arranged that the rider may exert a drawing as well as a pushing strain on the cranks.

In the drawings—

A represents the forward wheels of my tricycle, loosely journalled on the ends of the cranked axle B, which rotates in the bearings c at the ends of the forked reach C.

To the rear end of this reach is rigidly secured the hollow standard D, in which is journalled another hollow standard, E, from which depend the axle-jaws e, in the lower ends of which are journalled the ends of the axle of the guiding or steering-wheel F.

G is a tiller-rod, passing down within the hollow standard E, and terminating in a brake, g, bearing against the periphery of the wheel when a downward pressure is exerted on the rod, but kept up from it by a spiral spring, a, coiled about the hollow standard E, with its lower convolution pressing against the upper edge of the standard D, while its upper presses against a pin, b, projecting from the tiller, through an appropriate slot in the hollow standard E.

The tiller-rod is bent over and forward, and projects down in front of the rider, with its handle in easy

reach. By turning the tiller-rod, the course of the rear wheel is changed, while by pulling it down the brake is brought to bear upon the wheel.

H is a seat, supported by suitable rods attached to the forks of the reach.

I are stirrups, sleeved on the wrists of the cranks of the driving-axle, and provided with heel-straps i, so that the rider, after pushing the crank forward and down past the centre, may impart an additional impulse to the crank, by drawing with his foot against the heel-strap.

To maintain the heel-strap in its proper position relative to the rider's foot, the stirrups are weighted on their under sides, as shown.

The driving-wheels being loose upon the axle, to communicate a forward motion to them, on the inner ends of the hubs I place a spring-pawl, n, engaging with the teeth of a ratchet, o, secured to the driving-axle.

By this arrangement, the forward motion of the cranks is communicated to the wheels, but in making a short turn, the inner wheel is allowed to stand still, while the outer describes the arc of a circle.

What I claim as my invention, and desire to secure by Letters Patent, is—

The tiller G, curved for the purpose of bringing its handle over and in front of the rider, in connection with the guiding-wheel F, substantially as and for the purpose aforesaid.

Also, in combination with the weighted stirrups I, the heel-straps i; when constructed and operating as above described.

Also, in combination with the above-named tiller G, guiding-wheel F, weighted stirrups I, and heel-straps i, the arrangement of the wheels A, cranked axle B, rotating in the bearings c of the bifurcated reach C, hollow standard D, pawls n, ratchets o, and seat H, when constructed and operating as and for the purpose above set forth.

EDGAR A. JONES.
